H. G. Manning
ATTORNEY

UNITED STATES PATENT OFFICE.

JAMES B. GRIFFIN, OF WATERBURY, CONNECTICUT.

VANITY BOX.

Application filed May 20, 1926. Serial No. 110,389.

This invention relates to toilet articles, and more particularly to a vanity box adapted to be carried in the pocket or lady's hand bag.

- 5 One object of the invention is to provide a vanity box adapted to contain loose face powder, said powder being carried in an outer annular chamber, the top of which is closed by a depressible plate.
- 10 A further object of the invention is to provide a device of the above nature which will be simple in construction, inexpensive to manufacture, easy to manipulate, compact, ornamental in appearance, and very 15 efficient and durable in use.

With these and other objects in view there has been illustrated on the accompanying drawing one form in which the invention may be conveniently embodied in practice.

- 20 Fig. 1 represents a top plan view of the vanity box as it appears in open position, the cover of said box being shown partly broken away.

Fig. 2 is a side view of the same.

- 25 Fig. 3 is a side sectional view of the vanity box as it appears when the cover is in closed position.

- 30 Fig. 4 is an enlarged sectional fragmentary view of a portion of the vanity box showing the plate depressed for permitting loose powder to flow out of the chamber upon the top of said plate.

- Fig. 5 is a fragmentary view of a portion of the body member and the closure for the 35 powder chamber showing the bayonet slot and pin arrangement for locking said parts together.

- Many ladies prefer to use loose face powder instead of the solid "compacts" now commonly provided with the vanity boxes now on the market. By means of the vanity box provided by the present invention, a lady will be permitted to employ her own favorite brand of loose powder, and the use of 45 the powder will be greatly facilitated.

- Referring now to the drawings in which like reference numerals denote corresponding parts throughout the several views, the numeral 10 indicates a hollow base member, 50 preferably cylindrical in shape, and having a flat base 11. The top of the base member 10 is closed by a cup-shaped cover member 12 which is pivotally connected to the body member 10 by a hinge 13.

- 55 In order to provide space for receiving a

considerable quantity of loose face powder 14, an outer annular chamber 15 is provided in the vanity box, said chamber being defined by the outer wall of the body member 10 and a central wall member 16, said wall member 16 having a flat base flange 17 adapted to be soldered or otherwise secured to the base 11 of the body member 10. Soldered or otherwise secured to the top of the central wall member 16 is an outwardly flared 60 fixed member 18 which forms a seat for a detachable closure member 19.

The closure member 19 has an outer depending flange 20 adapted to be detachably locked within the outer rim of the body 70 member 10 by a pair of oppositely disposed pins 21 engaging in bayonet slots 22 as clearly shown in Figs. 3 and 5.

The annular chamber 15 is divided into two compartments by a pair of partition 75 plates 23 and 24 located on opposite sides of said chamber.

In order to permit loose face powder to be released from the chamber 15, the central wall member 16 is provided with a pair of 80 cut-out slots 25 and 26 extending substantially entirely around the circumference of said wall member except for a pair of supporting legs 27, one of which is shown in Fig. 4. The slots 25 and 26 are normally 85 closed by a concave plate 28 which is fitted within the space inside of the central wall member 16, said plate 28 having its outer edge turned downwardly for a short distance at 29 and slidably fitted within said section 90 16. The flange 29 on the plate 28 is adapted to engage an inwardly extending annular rib 30 on the wall member 16 to prevent the plate 28 from being pushed too far downwardly. The top edge of the plate 28 is prevented from sliding out of position by an inwardly extending flange 31 on the fixed member 18, said concave plate 28 being pressed upwardly against said flange 31 at all times by a spiral spring 32 resting on 100 the bottom 11 of the base member 10.

In operation, when it is desired to fill the vanity box with face powder, the outer cover 12 will be first swung up about its hinge 13 to the position shown in Figs. 1 and 2. The 105 annular closure member 19 will then be twisted until the pins 21 come into alignment with the vertical parts of the bayonet slots 22, whereupon said cover may be removed 110 permitting the chamber 15 to be then re-

plenished with loose powder. The closure 19 may then be replaced and relocked in position.

In using the vanity box, a powder puff 33 which is adapted to rest in the concave plate 28 will first be raised, and the user will then press downwardly with her finger upon the central part of the plate 28 against the tension of the spring 32. As will be understood, this pressure will force the plate 28 downwardly, uncovering the slots 25 and 26. The user will then tap the case lightly causing a small quantity of loose powder to sift out through said slots upon the central portion of the concave plate. The plate 28 will then be released allowing the spring 32 to return it to its upper normally closed position in contact with the flange 31. The powder on the plate may then be taken up by the powder puff and applied to the face.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a vanity box, a hollow base member having a cover hinged thereto, a ring member located in the center of said base member, said ring member and the rim of said base member defining a powder-containing chamber, a detachable closure for the top of said chamber, said ring member having openings therein, a plate fitting within said ring member for receiving powder through said openings when said plate is depressed, and means for raising said plate to cover said openings.

2. In a vanity box, a hollow base member having a cover hinged thereto, a ring member located in the center of said base member, said ring member having a bottom flange secured to said base member, said ring member and the rim of said base member defining a powder-containing chamber, a detachable closure for the top of said chamber, said ring member having openings therein, a plate fitting within said ring member for receiving powder through said openings when said plate is depressed, and spring means for raising said plate to cover said openings.

3. In a vanity box, an outer powder chamber having a central space therewithin, said chamber having openings communicating

with said central space, a spring-pressed plate adapted to slide downwardly into said central space for uncovering said openings whereby powder will be allowed to pass out of said openings upon the top of said plate from which it may be readily removed upon a powder puff.

4. In a vanity box, an outer powder chamber having a central space therewithin, said chamber having openings communicating with said central space, a cup-shaped spring-pressed plate adapted to slide downwardly into said central space for uncovering said openings whereby powder will be allowed to pass out of said openings upon the top of said plate from which it may be readily removed upon a powder puff.

5. In a vanity box, a hollow base member, a ring member located therein, said ring member and the rim of said base member defining a powder-containing chamber, a sliding plate in said ring member, spring means for pressing said plate upwardly, said ring member having openings normally closed by said plate to permit powder to pass out upon the top of said plate when the latter is depressed.

6. In a vanity box, a hollow base member, a ring member located therein, said ring member and the rim of said base member defining a powder-containing chamber, a sliding plate having a depending outer flange fitting within said ring member, spring means for pressing said plate upwardly, said ring member having openings normally closed by said plate to permit powder to pass out upon the top of said plate when the latter is depressed.

7. In a vanity box, a hollow base member, a ring member concentric therewith, said ring member and the rim of said base member defining a powder-containing chamber, a sliding plate in said ring member, spring means for pressing said plate upwardly, said ring member having an opening normally closed by said plate to permit powder to pass out upon the top of said plate when the latter is depressed, and means on said ring member for limiting the upper and lower positions of said sliding plate.

8. In a vanity box, a hollow base member having a cover, a ring member located in said base member, a loose-powder-containing chamber surrounding said ring member, said ring member having an opening, a depressible plate telescoping in said ring member for receiving powder from said chamber through said ring member when said plate is depressed, and means to press said plate upwardly to cover said opening.

In testimony whereof, I have affixed my signature to this specification.

JAMES B. GRIFFIN.
